GAS LIFT

Filed April 6, 1925

UNITED STATES PATENT OFFICE

WILLIAM R. STUCK, OF LOS ANGELES, CALIFORNIA

GAS LIFT

Application filed April 6, 1925. Serial No. 21,216.

This invention relates to gas lifts for elevating fluids from wells and is more particularly directed to an apparatus for raising oil from deep oil wells employing a gas lift wherein the gas is admitted into the fluid string at a point normally above the level within the well and wherein an oil well pump of any desired construction is employed to raise the oil from within the well in the fluid string above the point of the admission of the gas.

An object of this invention is to provide a simple and durable construction of apparatus for admitting gas into the fluid string at a point above the normal level of the fluid within the well so as to elevate the fluid to the surface of the well.

An object of this invention is to provide a connecting collar construction in which means are provided for admitting air into the fluid string when the collar is in position and in which there is also provided a simple and effective means for controlling the direction of the flow through the gas admitting means.

Another object of this invention is to provide a check valve adapted to be connected with a collar and when so connected does not materially weaken the collar or materially decrease the clearance of such a collar when the same is positioned in the well.

Other objects and advantages of this invention will be apparent from the following detailed description of a preferred embodiment thereof as illustrated in the accompanying drawings.

In the drawings:

Fig. 1 is a diagrammatic side elevation of a well illustrating the fluid string as partly in section so as to show the approximate position of the pump plunger within the well.

Fig. 2 is a central sectional side elevation of a collar illustrating the same as connecting two fragments of a fluid string and illustrating a check valve embodying this invention attached thereto.

Fig. 3 is a top plan view thereof, taken substantially on the line 3—3 of Fig. 1.

Fig. 4 is an enlarged central sectional front elevation of a check valve embodied in this invention.

In the preferred embodiment of this invention illustrated in the drawings, 1 indicates a well casing, 2 the well tubing or fluid string, and 3 sucker rods, connected to an oil well pump piston 4 of any suitable construction at the lower end and connected to a walking beam 5 in any desired manner at the upper end. A T or head 6 is connected to the fluid string 2 at its upper end and is connected with a pipe 7 to which the oil pumped from the well is carried to a tank 8. Connected to the upper end of a casing 1 is a casing head 9 which is connected to a gas conduit 10, which gas conduit connects to a pump 11 which pump 11 takes the gas collected above the oil in the tank 8 through a pipe line 12 and pumps the same under pressure through the pipe 10 and casing head 9 into the well casing 1 on the exterior of the fluid string 2. A collar 13 in which a check valve 14 is secured is connected in the fluid string 2 in a position substantially at the level of the oil within the well.

The collar 13 and the check valve 14 are preferably of the following construction and manner of assembly:

The collar 13 is planed as illustrated at 15 to form a recess within which a check valve block 16 is adapted to closely fit. The check valve block is spot welded within the recess 15 around its entire edge so that the same is formed integral with the collar 13 and does not materially decrease the strength of the collar 13. The block 14 is preferably constructed as illustrated in Fig. 4, and a port 17 is bored through the lower end of the block 16 and is bored approximately at the center to form a port 18 which communicates with the port 17. The port 18 is reamed to form an enlarged chamber 19 in which a ball 20 is positioned, the upper end of the walls of the port 18 being cut away to form a seat 21 for the ball 20.

A plug 22 is inserted within the port 18 above the chamber 19 and is securely welded in position. A gas outlet port 23 is bored from the rear of the block 16 to communicate with the chamber 19 and a bore 24 is formed through the collar 13 in position to commu-

nicate with the port 23 when the block 16 is positioned within the recess 15.

The operation of my gas lift is as follows: The oil pump 4 actuated from the walking beam 5 raises the fluid within the well to a position above the collar 13. Gas under pressure from the pump 11, or any other suitable source of gas pressure, flows through the ports 17, 18, raises the ball valve 20 from its seat and passes through the port 23 and bore 24 and is injected into the interior of the collar 13 into the oil raised by the pump 4. The buoyancy of the gas and the pressure thereof raises the fluid from this level through the fluid string to the head 6, through the pipe 7 into the tank 8 where the gas separates from the oil and is again used for the purpose of supplying the fluid pressure for actuating the gas lift.

20 In practice, the bore 17 in the block 16 for use with a $2\frac{1}{2}$ " collar is preferably $1\frac{3}{16}$ " in diameter. The bore 18 is preferably $\frac{1}{4}$ " in diameter so that the combined area of the two leads from the opposite sides of the block 16 through the port 17 have a combined cross sectional area slightly in excess of the cross sectional area of the port 18. The port 23 is of smaller cross sectional area than the port 18 so that the gas is injected into 30 the interior of the collar 13.

Having fully described a preferred embodiment of this invention, it is to be understood that I do not wish to be limited to the exact construction and illustrative sizes of 35 construction, which may, obviously, be varied in detail without departing from the spirit of my invention, but the same is of the scope of the appended claims.

I claim:

40 1. In an apparatus of the kind described, the combination with a gas lift of a fluid string, a collar in said string, a check valve in said collar, said check valve comprising a block having a longitudinally extending passage through its lower end, a vertical port approximately centrally disposed in the block and communicating at its lower end with the longitudinal passage and at its upper end with a valve chamber, and a transversely 45 extending port for establishing communication with the valve chamber and the interior of the collar.

2. In combination with a gas lift, a fluid string, a collar in said string having a recess formed therein, and a check valve block adapted to be secured in position in said recess and having a longitudinally extending passage through its lower portion, a vertical 55 port approximately centrally disposed in the block, and communicating at its lower end with the longitudinal passage and at its upper end with a valve chamber, a ball check valve mounted within the chamber, and a transversely extending port for establishing 60

communication between the valve chamber and the interior of the said collar.

Signed at Los Angeles, California this 26th day of March, 1925.

WILLIAM R. STUCK.
